UNITED STATES PATENT OFFICE.

JOHN HENRY SANDLAS, OF BALTIMORE, MARYLAND.

DESIGN FOR A PIANO-CASE.

No. 37,592.

Specification for Design.

Patented Oct. 24, 1905.

Application filed August 21, 1905. Serial No. 275,188. Term of patent 14 years.

To all whom it may concern:

Be it known that I, JOHN HENRY SANDLAS, a citizen of the United States, and a resident of and whose post-office address is No. 225 Myrtle avenue, in the city of Baltimore and State of Maryland, have invented a new, original, and ornamental Design for Piano-Cases, of which the following is a specification, reference being had to the accompanying drawing, forming a part thereof.

The figure is a perspective view of a piano, showing my new design.

I claim—

The ornamental design for a piano-case, as shown.

JOHN HENRY SANDLAS.
